UNITED STATES PATENT OFFICE.

JOHN W. DEWEES, OF PHILADELPHIA, PENNSYLVANIA.

FABRIC-TRIMMER.

SPECIFICATION forming part of Letters Patent No. 355,148, dated December 28, 1886.

Application filed November 30, 1883. Serial No. 113,169. (No model.)

To all whom it may concern:

Be it known that I, JOHN W. DEWEES, a citizen of the United States, residing at the city of Philadelphia, in the county of Philadelphia and State of Pennsylvania, have invented certain new and useful Improvements in Fabric-Trimmers; and I do hereby declare the following to be a full, clear, and exact description of the invention, reference being had to the accompanying drawings, which form part of this specification, in which—

Figure 1 is a front elevation of a sewing-machine with my improvements applied. Fig. 2 is a detail view of mechanism for rocking shaft. Fig. 3 is a side elevation, with cloth-plate in section, of a sewing-machine with my improvements applied. Fig. 4 is a detail of a modification, and Fig. 5 a plan, partly broken away, of presser-foot.

My invention has for its object to effect the trimming of hosiery or other fabric by abrasion or rupture, as set forth in Letters Patent of the United States heretofore granted to me, dated October 31, 1882, but by means which constitute a modification of the special mechanism shown and described in said Letters Patent. In said Letters Patent are shown and described two toggle-levers with blunt opposing edges and means for rocking the same to effect the separation of the fabric. Such rocking action produces a blow, in the same sense as a car-wheel in rolling upon a track strikes or pounds the latter. I have discovered that the same substantial effect as is produced by the rocking of the edges of two blunt levers—that is to say, the separation or rupture by abrasion of a fabric—may be secured by mechanism in which the actuating devices consist of an anvil or bar and a hammer or striker.

My invention consists in the combination, with the stitch-forming mechanism of a sewing-machine, of a trimmer comprising a straight-edged blunt jaw or anvil having its edge parallel with the line of feed, a flat-faced hammer or striker which contacts with said anvil or jaw, and means for reciprocating said striker or movable jaw, the latter and the anvil on which it strikes being composed of metal sufficiently hard to resist the crushing action of the opposing impinging surface and operating to trim fabric by rupturing, crushing, or abrad-

ing the latter, substantially as hereinafter described.

Referring to the accompanying drawings, A represents a sewing-machine which in the 55 illustration is a Willcox & Gibbs machine, but may be obviously any other well-known or suitable sewing-machine. B is the bed-piece of said machine; C, the cloth-plate, and D the main shaft. To the face or end of said bed-piece there is rigidly secured in any suitable manner an upright, E, which is shown as fastened by screws e. Said upright has its end projecting through a slot or opening, c, in the cloth-plate C. Said upper end may be on a 60 level with the upper surface of plate C, or it may project a slight distance—say one-thirty-second of an inch—above such plate. This upright constitutes an anvil or striker-bar, and its upper edge may be blunt or flat, rounded, 65 or beveled.

F represents a hammer or striker, consisting of a handle or lever having one end fastened to a rock-shaft, G, its other end having a head, H. Said head H may be caused to strike directly on the anvil or bar E; but I prefer to provide it with a bit, h, fitted in a groove, h', in said head and adjustably secured thereto by a screw, h'', passing through a slot, h', in said bit and entering a threaded opening in the 80 head H.

When the shaft G rocks, the bit h strikes the anvil or bar E, and if fabric be interposed between said bit and anvil it will be separated by the blow, and if such fabric be fed along, 85 as when being sewed on a machine, the rupture produced will be a clean line or edge. To rock the shaft G it is furnished with an arm, g, pivotally connected with a lever, I, having a strap or collar, i, encircling an eccentric, K, 90 on main shaft D; or, as a modification, (shown in Fig. 4,) the arm g may be held by a spring, L, in contact with a cam, M, on said shaft, whereby the shaft G will be rocked as shaft D rotates.

The motion of the trimmer will be so timed relatively to the sewing-machine that the striker or hammer and the needle will rise and fall together, or so that said striker will be elevated when the fabric operated on is being 95 fed.

N represents the presser-foot provided with

a lateral extension, *n*, which flares or rises toward its front edge, so as to cause the fabric to pass readily under it. This presser-foot is arranged relatively to the trimmer so that 5 the latter will be back of or inside the extension *n*, said extension thus operating as a flat-tener to take out the curl from the fabric fed to the trimmer.

The manner of operating the sewing-machine with the trimmer and presser-foot herein described is the same as with machines having other styles of trimmers; but the manner in which the trimmer operates is different from that of any trimmer produced previous to my 15 invention. As already stated, separation of the fabric in the present case is produced by a rupturing or abrading action, as with my aforementioned patented trimmer; but in the present case the rupturing results from the direct 20 blow of a rising-and-falling hammer, while in the patented trimmer the same result is accomplished by the rocking action of two levers.

The hammer and anvil herein described are composed of hard material—such as is usually 25 employed as the constituents of hammers and anvils—in order that they may perform their functions as trimmings-jaws, operating to effect the division of fabric by rending, crushing, or rupturing the latter by percussive, 30 crushing, or abrading action, as distinguished from cutting with a sharp edge or edges, and that they and each of them may be affected as little as possible by the attrition of the hammer or movable jaw or striker.

35 I am aware that it has been heretofore proposed to trim fabrics by what are known as "choppers," in which a sharp-edged knife or chisel is caused to descend upon a plate of metal—such as lead or brass—which, while comparatively hard, is yet sufficiently soft to permit the use of a soft cutting-tool, and particularly that such a trimmer was constructed by James E. Wilson, of Chicago, Illinois, the blade being sharp-edged, and the resistance-plate or 40 opposing surface or die being brass—a construction usually adopted in button-hole cutters; but my invention differs therefrom in that in my case both the impinging surfaces are of metal sufficiently hard to resist the 45 crushing action of the impinging surfaces, thus producing a rupturing or crushing operation, while in the Wilson and button-hole cutters the resistance-plate is of comparatively soft metal. The resistance-plate in the Wilson device was made of brass. The movable chisel, 50

being harder metal and having a sharp edge, indented and injured the soft plate and soon rendered the cutting process imperfect and unsatisfactory.

What I claim as my invention is as follows: 6,

1. In a sewing-machine trimmer, the combination, with the stitch-forming mechanism, of a straight-edged blunt trimming-jaw having its edge parallel with the line of feed, a flat-faced hammer or striker arranged above said trimming-jaw, and means whereby said hammer is continuously reciprocated during the sewing operation, so as to strike squarely against said trimming-jaw, said striker or hammer and jaw being composed of metal 65 sufficiently hard to resist the crushing action of the opposing impinging surface, and operating to trim fabric by rupturing, crushing, or abrading the latter, substantially as shown and described. 70

2. In combination with the stitch-forming mechanism of a sewing-machine, an anvil or support adjacent thereto having its supporting-surface parallel with the line of feed, a blunt hammer or striker above said anvil, and a mechanism for reciprocating said hammer so as to cause it to strike against said anvil or support, said anvil and hammer being composed of metal sufficiently hard to resist the crushing action of the opposing impinging 85 surface, and operating to trim fabric by rupturing, crushing, or abrading the latter, substantially as shown and described. 80

3. In combination with the stitch-forming mechanism of a sewing-machine, an anvil or support adjacent thereto having its supporting-surface parallel with the line of feed, and a hammer or striker, with mechanism for producing a reciprocating movement thereof, whereby by said hammer or striker and said anvil are 90 made to impinge one against the other, said anvil and hammer or striker being composed of metal sufficiently hard to resist the crushing action of the opposing impinging surface, and operating to trim fabrics by rupturing, 95 crushing, or abrading the latter, substantially as described. 100

In testimony that I claim the foregoing I have hereunto set my hand this 28th day of November, 1883.

JOHN W. DEWEES.
